UNITED STATES PATENT OFFICE

158,373

ROADSIDE STORE BUILDING

Alice J. Grossniklaus, Wilmot, Ohio

Application March 10, 1949, Serial No. 1,321

Term of patent 14 years

(Cl. D13—1)

To all whom it may concern:

Be it known that I, Alice J. Grossniklaus, a citizen of the United States, residing at Wilmot, in the county of Holmes, and State of Ohio, have invented a new, original, and ornamental Design for a Roadside Store Building, of which the following is a specification, reference being had to the accompanying drawing forming part thereof.

Fig. 2 is an elevational view of one side thereof;

Fig. 3 is an elevational view of the opposite side thereof; and

Fig. 4 is a perspective view thereof.

The rear of the building is substantially similar to the front as shown in Figs. 1 and 4.

I claim:

The ornamental design for a roadside store building, substantially as shown and described.

ALICE J. GROSSNIKLAUS.
